SUPPORT FOR GEIGER-MUELLER COUNTERS

Ernest H. Wakefield, Chicago, Ill., assignor to the United States of America as represented by the United States Atomic Energy Commission

Application December 11, 1945, Serial No. 634,309

5 Claims. (Cl. 250—83.6)

1

This invention relates to novel apparatus for supporting a Geiger-Mueller counter in its shield.

Shields for Geiger-Mueller counter's usually are in the form of a lead cylinder with end closures, one of which may be opened to admit the counter. The radioactive sample is either placed in the shield below the counter tube or is wrapped around it. Both for servicing and for wrapping samples on the tube, it is necessary to remove the tube from the shield.

It is one of the objects of the present invention to provide a novel support by means of which a counter tube can be supported in proper position in a shield and can be withdrawn and re-inserted readily, whereby handling is facilitated, short circuits of the electrical circuits are rendered less likely, and the tube itself and the seal between the tube and its external conductors are protected.

Another object is to provide a novel support of the character described which can be used for counters having tubes of various sizes and materials.

Other objects and advantages will become apparent from the following description wherein reference is made to the drawings, in which:

Fig. 1 is a longitudinal sectional view of a Geiger-Mueller counter shield with the support of the present invention and a counter tube installed therein;

Fig. 2 is an enlarged side elevation of the support and tube; and

Fig. 3 is an enlarged cross sectional view taken on line 3—3 of Fig. 2.

Referring to the drawings, the usual cylindrical shield 1 is illustrated in Fig. 1 and preferably is in the form of a lead cylinder about 12 inches long and 6 inches in outside diameter with a wall thickness of about 1 inch. The cylinder 1 is closed permanently at one end and is closed at the other end by a swinging lid 2.

A Geiger-Mueller counter is shown having an elongated tube 3, usually of glass or aluminum, in which is disposed a high voltage electrode 4 which is coaxial with the tube. A high voltage conductor 5 is connected to one end of the electrode 4 and extends to the outside of the tube, the conductor 5 and the end of the electrode connected thereto being sealed into the end wall of the tube 3. The other end of the tube is sealed and the interior wall of the tube is coated with a silver coating, indicated at 6, from which a conductor 7 leads through the circumferential wall of the tube for connection in an external scaler circuit (not shown). It is apparent that the seals be-

2

tween the tube and each of the conductors 5 and 7 may be damaged easily by tension applied to the conductors, especially when the tube is glass.

The support with which the present invention is particularly concerned comprises a rod 10 of metal, such as brass, one end of which is mounted in the fixed end wall of the shield 1 at a point offset from the center of the end wall. The rod 10 extends partway along the inside of the shield 10 parallel to the shield axis but spaced therefrom and from the circumferential wall of the shield 1.

Mounted on and dependent from the rod 10, for sliding movement therealong, is a clamp 11. The clamp 11 preferably is of insulating material, such as "Bakelite," and comprises an upper portion 12 and a lower portion 13 which, when fastened together by screws 14, define a bore 15 in which the tube 3 may be frictionally secured, proper shims being used if desired for obtaining the desired clamping pressure between the portions 12 and 13 and the tube 3. For slidably mounting the clamp 11 on the rod 10 and at the same time providing a sliding electrical connection between the conductor 7 and the rod 10, a metal sleeve 16 is provided. A slot 17 is provided in the rod 10 and is engaged by a pin 18 of the clamp for retaining the clamp in proper position circumferentially of the rod 10.

Mounted on the clamp 11 is a bracket 19 to which is fixedly secured an insulating sleeve 20 through which extends an external high voltage conductor 21 which is clamped in place in the sleeve 20 by a set screw 22. One end of the conductor 21 is provided with an alligator clamp 23 for detachably engaging the conductor 5. The other end of the conductor 21 extends through a polystyrene fitting in the end wall of the shield for connection to an external scaler circuit (not shown).

The high voltage conductor 21 is coiled at 24 to permit withdrawal of the support from the shield.

The rod 10 is grounded in the shield 1 and thus grounds the conductor 7.

For convenience in sliding the counter along the rod 10, a suitable insulating handle 25 is provided and so positioned as to be readily accessible from the end of the shield 1 which is closed by the lid 2.

Since the conductor 21 is anchored firmly to the bracket 19, no stress is transmitted to the conductor 5 or to the tube 3 by the conductor 21 when the counter is slid along the rod 5.

The danger of short circuits due to jamming the conductors against the closed end of the shield is further reduced by provision of a stop

collar 26 on the rod 5 which limits the inward movement of the clamp 11.

Having thus described the invention, what is claimed is:

1. A support for a Geiger-Mueller counter tube comprising an insulating clamp member adapted to be rigidly clamped to the tube, a supporting rod of electrically conducting material, a sleeve of conducting material rigidly attached to the clamp member and slidable therewith along the supporting rod and a conducting connector fixedly attached to the clamp member, whereby the electrodes of the tube may be electrically connected to an associated circuit by connection to said sleeve and connector respectively but are mechanically fixed in relation to the said clamp member and tube.

2. A support for a Geiger-Mueller counter tube comprising an elongated supporting member of electrically conducting material, an insulating clamp member adapted to be rigidly clamped to a counter tube, a slide member of electrically conducting material fixedly secured to the clamp member and slidably engaging the supporting member, an external conductor, connecting means on one end thereof for detachably engaging a conductor of the counter tube, and means securing said end of the external conductor rigidly to the clamp member, whereby the electrodes of the tube may be electrically connected to an associated circuit by connection to said slide member and external conductor respectively but are mechanically fixed in relation to said clamp member and tube.

3. In combination, a Geiger-Mueller counter tube, an elongated radiation shield, an elongated rigid support mounted in one end of the shield and extending lengthwise in the shield cavity, a clamp slideable along said support, a counter tube rigidly secured to the clamp, an insulated external conductor extending into the shield cavity and connected to a conductor of the tube, and means on the clamp securing one end of the external conductor in fixed position relative to the tube, whereby tension on the external conductor is transmitted only to the clamp.

4. In combination, a Geiger-Mueller counter

tube, an elongated radiation shield, an elongated rigid support mounted in one end of the shield and extending lengthwise thereof in the shield cavity, a clamp slideable along said support,

5. a counter tube rigidly secured to the clamp, an external insulated conductor extending into the shield cavity and connected to a conductor of the tube, means on the clamp for securing one end of the external conductor in fixed position relative to the tube, said elongated rigid support being of electrically conducting material, and electrical conducting means rigid with the clamp and connected to another conductor of the tube and in sliding contact with said support, whereby the tube may be moved along the support and remain free of tension on its conducting leads.

10. 5. In combination, a Geiger-Mueller counter tube, an elongated radiation shield openable at one end, an elongated rigid support mounted in the other end of the shield and extending lengthwise thereof in the shield cavity, a clamp slideable along said support, a counter tube rigidly secured to the clamp, an external insulated conductor extending into the shield cavity and connected to a conductor of the tube, means on the clamp securing one end of the external conductor in fixed position relative to the tube, and a handle of electrically insulating material on the clamp and extending toward said openable end of the shield, 15. 30. whereby the tube may be moved along the support and remain free of tension on its conducting leads.

ERNEST H. WAKEFIELD.
